UNITED STATES PATENT OFFICE.

JOHN L. TAYLOR, OF BOZEMAN, MONTANA.

APPARATUS FOR LIFTING WAGON-BOXES, &c.

SPECIFICATION forming part of Letters Patent No. 698,338, dated April 22, 1902.

Application filed February 8, 1902. Serial No. 93,238. (No model.)

26 *all whom it may concern:*

Be it known that I, JOHN L. TAYLOR, a citizen of the United States, residing at Bozeman, in the county of Gallatin and State of Montana, have invented certain new and useful Improvements in Apparatus for Lifting Wagon-Boxes, &c.; and I do declare the following to be a full, clear, and exact description of the invention, such as will enable others skilled in the art to which it appertains to make and use the same, reference being had to the accompanying drawing, and to the letters of reference marked thereon, which forms a part of this specification.

15 This invention relates to new and useful improvements in hoisting devices, and especially to an apparatus for lifting wagon-boxes and various other articles; and it consists in the provision of a movable standard which is mounted, preferably, upon wheels and is provided with handles whereby the device may be moved from one place to another and adjacent to the wagon-box or other articles to be moved and in the provision of a windlass suitably mounted on the standard and about which windlass a rope or chain having hooks connected thereto is adapted to be wound by means of a hand-wheel having gear connection with the windlass.

20 To these ends and to such others as the invention may pertain the same consists, further, in various details of construction, and combination of parts, as will be hereinafter more fully described and then specifically defined in the appended claim.

35 My invention is clearly illustrated in the accompanying drawing, in which I have shown a perspective view of my improved lifting device.

40 Reference now being had to the details of the drawing by letter, A designates the platform upon which the upright posts B are mounted and suitably braced, as illustrated. A cross-beam C connects the upper ends of 45 said upright posts, which cross-beam is also braced and mounted in the bearings D, which are fastened to the side of the said upright posts. Near their upper ends is a windlass E, to which one end of the chain or rope T is 50 adapted to wind as the windlass is rotated. Keyed to one end of said windlass is a gear-wheel G, which is in mesh with a worm-wheel

H, which is mounted upon and rotates with the shaft K, which shaft is mounted, preferably, at an inclination in bearings in the 55 cross-piece N and cross-piece at the upper ends of said upright posts. A hand-wheel for rotating said shaft is keyed or otherwise fastened to the lower end of said shaft, and a collar or washer O is fastened to said shaft 60 at a location adapted to rest upon the cross-piece N and is provided for the purpose of holding said shaft, so that the worm-wheel on the shaft will be held in mesh with said gear-wheel at the end of the windlass. The upper 65 face of said cross-piece N is notched, as at N', so that the under face of said collar or washer will rest flat against the inclined face of the notch.

70 Mounted under the end pieces of the platform or frame are wheels Q, while intermediate the length of the longitudinal portion of the standard-supporting frame is a leg R, which co-operates with said wheels to hold the frame horizontally. Handles F project laterally from the longitudinal side beam of the frame, as shown, whereby one side of the 75 device may be lifted to throw the weight upon the wheels when it is desired to move the lifting apparatus from one location to another. 80

By the peculiar construction of the framework of my improved lifting apparatus, in which one side is open, it will be observed that the device may be moved so as to partially surround a wagon-box or other articles 85 to be lifted, and by means of the hooks W, which are fastened to the ends of the ropes or chains connected to the hoisting rope or chain, the article to be lifted may be easily raised by manipulating the hand-wheel, 90 which will cause the rope or chain to wind upon the windlass.

Having thus described my invention, what I claim to be new, and desire to secure by Letters Patent, is—

95 A device for lifting wagons and other articles, comprising a frame open upon one side, wheels mounted under the ends of said frame, and a leg intermediate the closed longitudinal side of the frame, whereby said frame 100 may be held in a horizontal plane, handles projecting from the edge of said closed side, upright posts mounted on the ends of the frame and suitably braced, a windlass jour-

naled on said upright posts, a rope or chain secured to and adapted to wind upon said windlass and provided with hooks fastened to the end of said rope or chain, a gear-wheel 5 keyed to the end of the windlass, a shaft, a worm-wheel rotating with said shaft and in mesh with said gear-wheel, a hand-wheel for rotating said shaft, a collar or washer fastened to said shaft, a cross-piece fastened to 10 one of said uprights and the braces thereto, the

upper face of said cross-piece being notched, the under face of said collar or washer adapted to rest flat against the inclined face of said notched portion as shown and described.

In testimony whereof I hereunto affix my 15
signature in presence of two witnesses.

JOHN L. TAYLOR.
